United States Patent Office.

ALEXANDER JACK, OF MILTON, NEW HAMPSHIRE, ASSIGNOR TO HIMSELF
AND EDWARD BRIERLEY, OF SAME PLACE.

Letters Patent No. 69,098, dated September 24, 1867.

IMPROVED MODE OF DYEING AND EMBOSSED TABLE AND PIANO-COVERS.

The Schedule referred to in these Letters Patent and making part of the same.

TO ALL PERSONS TO WHOM THESE PRESENTS MAY COME:

Be it known that I, ALEXANDER JACK, of Milton, in the county of Strafford, and State of New Hampshire, have made a new and useful Improvement in the Production of Table-Cloths, Piano-Covers, or other articles of like character; and I do hereby declare the nature of my invention, and the manner in which it is to be performed, to be fully described in the following specification and represented in the accompanying drawings, of which—

Figure 1 is a side elevation, and

Figure 2 a horizontal section, and

Figure 3 a transverse section of a dye-frame as used in carrying out my invention.

Figure 4 is a top view of a piano-cover or piece of cloth as dyed by such frame, preparatory to being embossed or printed or embossed and printed, as circumstances may require.

The dye-frame used by me, in my process of making a piano or table-cover, is like such as are employed for dyeing flannels or other fabrics in stripes or plaids, except that the parts thereof employed for compressing portions of the cloth, so as to prevent the coloring liquid from entering such portions while it permeates the rest of the cloth, are to be of the forms required to produce the undyed spaces or medallions which it may be desirable to have in the cloth. In fig. 4 these medallions or undyed spaces are shown at *a a a*, &c., *b* being the portion which is to be dyed.

In figs. 1, 2, and 3 the dyeing-frame is exhibited as partly composed of a series of open frames, *a a a*, arranged one over the other, and provided with clamp-blocks or projections *b b b*, the clamp-blocks of one frame, *a*, being directly upon and over those of the frame *a* below it. The pile of such frames is to be placed within *a*, being *A*, composed of a bed-plate, *c*, a follower, *d*, and a series of clamps, as shown at *B B B*.

The press, with its dye-frames so put together, and having a layer of cloth between each two of the dye-frames, is to be immersed in a dyeing liquid of the color required for the dyed ground, after which it is to be removed from the dyeing liquid and exposed to the atmosphere or other means of effecting the drying of the cloth or cloths.

After each piece of cloth has thus been dyed, with spaces or parts of it left undyed, it is to be embossed by an embossing press, or is to be printed in one or more colors and in such patterns or designs as may be desirable, or it may be embossed and printed at one and the same time.

My invention differs from that heretofore practised in the making of embossed and printed table-cloths, inasmuch as, instead of printing the grounds, I dye them by means as described, and thus even the color throughout and on both faces of the cloth. The process of printing the ground on the cloth is apt to leave uncolored spots or parts on the wrong side of the cloth. It is also objectionable in other respects. My improved process produces clear grounds, with edges defined and very favorable for reception of the imprints.

What, therefore, I claim is—

My improvement in the manufacture of printed table-cloths or other articles of like character, the same consisting in the combination of the process of dyeing by frames, as described, with that of embossing or printing the material so dyed, or those of embossing and printing, at one and the same time, as set forth.

I also claim the combination and arrangement of medallion or separate color-resisting blocks *b b b* with the common plaid or stripe-dyeing frames *a a a*, as described, whereby the stripe or plaid dye-frames may be used, as occasion may require, for dyeing cloths with grounds having undyed medallions, as set forth.

ALEXANDER JACK.
